(57) **CLAIM**

The ornamental design for a display rack as shown and described.

DESCRIPTION

FIG. 1 is a front, left and top perspective view of a display rack, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the display rack that form no part of the claimed design. The oblique line shading shown in the drawings indicates a transparent surface.
